The ornamental design for a grass shear, as shown and described.

DESCRIPTION

FIG. 1 is a front, left, top perspective view of a grass shear, showing our new design;

FIG. 2 is a rear, right, bottom perspective view thereof;

FIG. 3 is a front elevational view thereof;

FIG. 4 is a rear elevational view thereof;

FIG. 5 is a left side view of the enlarged scale thereof;

FIG. 6 is a right side view of the enlarged scale thereof;

FIG. 7 is a top plan view thereof;

FIG. 8 is a bottom plan view thereof;

FIG. 9 is an enlarged view of detail 9 in FIG. 1;

FIG. 10 is an enlarged view of detail 10 in FIG. 2; and,

FIG. 11 is an enlarged view of detail 11 in FIG. 7.

The dashed broken lines in the figures are for the purposes of illustrating portions of the grass shear and form no part of the claimed design.

The dot-dot-dash broken lines in the drawings define the bounds of the claim and form no part thereof.

The dash-dot-dash broken lines are for notating enlarged views and form no part of the claimed design.
